(57) CLAIM

The ornamental design for a backpack with hooks and saddle bags, as shown and described herein.

DESCRIPTION

FIG. 1 is a front elevation view of the backpack with hooks and saddle bags showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a left side perspective view thereof;

FIG. 8 is a right side perspective view thereof;

FIG. 9 is a front perspective closed interior view thereof; and,

FIG. 10 is a front perspective open interior view thereof. The broken lines on and adjacent to unshaded surfaces depict portions of the backpack with hooks and saddle bags and form no part of the claim. The broken lines on surfaces with surface shading depict stitching and zipper track and form no part of the claim.

1 Claim, 10 Drawing Sheets
